BASEBALL GLOVE

James Robert McTear, 32 Squadron Line,
Simsbury, Conn. 06070

Filed May 27, 1975, Ser. No. 580,844

Term of patent 14 years

Int. Cl. D2—06

U.S. Cl. D2—361

FIG. 1

FIG. 2

FIG. 1 is a front perspective view of a baseball glove showing my new design; and

FIG. 2 is a back perspective view thereof.

The characteristic feature of my design resides in the webbing portion shown.

I claim:

The ornamental design for a baseball glove, as shown and described.
